UNITED STATES PATENT OFFICE.

HENRY W. H. WARREN, OF COVENTRY, AND REGINALD NEWBOUND, OF RUGBY, ENGLAND, ASSIGNORS TO GENERAL ELECTRIC COMPANY, A CORPORATION OF NEW YORK.

INSULATING ROD.

Application filed June 21, 1927, Serial No. 200,457, and in Great Britain August 5, 1926.

Our invention relates to insulating rods and particularly to insulating rods which are used to support or operate electrical apparatus.

5 Insulating rods have been made in the past with reinforcing layers of fabric moulded therein and extending throughout the length of the rod, the reinforcement being provided for the additional strength which it gave to 10 the rod. While such a rod is thereby strengthened at the points at which connections are made thereto, for example at the ends of the rod, it is found that its insulating properties are impaired by the reinforcement and there is a tendency for the rods to split longitudinally between two adjacent 15 layers when the rod is subjected to large potential differences. An object of our invention therefore is to provide an insulating rod 20 for use such as described which shall avoid the aforesaid objections and have both the mechanical and the electrical strength desired.

Our invention will be better understood 25 from the following description taken in connection with the accompanying drawing, and its scope will be pointed out in the appended claims.

Referring to the drawing, Fig. 1 is a longitudinal cross section of one embodiment of 30 our invention and Fig. 2 is a similar view of a modified form.

In the drawing we have shown an insulating rod 1 which for example may comprise a portion of an oil switch such as the switch 35 operating rod. For illustrative purposes we have shown the rod 1 in Fig. 1 as the operating rod of an oil switch, the rod being provided with a socket member 2 at one end secured 40 to the rod by the rivets 3 and adapted to carry a cross head or other contact supporting member and provided at the other end with a clevis 4 by means of which it is pivoted at 5 to the member 6 which may be a 45 lever of a switch operating mechanism. The rod 1 is constructed of an insulating synthetic moulded compound, the central or body portion being uniform in composition while the end portions have embedded therein a reinforcement in the form of parallel insulating 50 layers 7 as for example of fabric. The layers

7 thus serve to reinforce mechanically the end portions of the rod where such reinforcement is desirable without lowering the insulation value of the intermediate portion of the rod 55 or rendering it liable to longitudinal splitting. We prefer to make the layers of varying lengths thereby to more securely embed them in the insulating compound.

In the modified form illustrated by Fig. 2 60 the rod 8 is adapted to have a connection made thereto at an intermediate point as well as the ends. It is here shown as a cross head of an oil switch having contacts 9 and 10 mounted on the ends thereof and supported 65 in the middle by the operating rod 11, the contacts being electrically connected together by the conducting strap 12. In addition to the reinforcing layers 7 at the ends of the rod 8 that part of the intermediate portion 70 which is secured to the rod 11 also is provided with reinforcing layers 13 which are similar to the layers 7. They also preferably have various lengths.

What we claim as new and desire to secure 75 by Letters Patent of the United States, is,—

1. In an electric switch, a rod of insulating material having portions adapted to receive mechanical connection, said portions of the rod being provided with a plurality of spaced 80 layers of reinforcing fabric, the extent of said layers being limited substantially to said portions.

2. In an electric switch, an insulating rod adapted to have mechanical connections made 85 to the ends thereof, said rod being constructed of synthetic insulating material having layers of reinforcing fabric arranged in and limited to the ends.

3. In an electric switch, an operating rod 90 adapted to be secured at its end portions respectively to the switch and the operating mechanism therefor, said rod being composed of synthetic insulating material having layers of fabric bonded in the end portions and 95 extending at various distances toward the intermediate portion.

In witness whereof, we have hereunto set our hands this first day of June, 1927.

HENRY W. H. WARREN.
REGINALD NEWBOUND,
